UNITED STATES PATENT OFFICE.

ALVA R. MERRICK, OF BLOSSBURG, PENNSYLVANIA.

HEAD-REST FOR DENTAL CHAIRS.

SPECIFICATION forming part of Letters Patent No. 333,019, dated December 22, 1885.

Application filed March 9, 1885. Serial No. 158,198. (No model.)

To all whom it may concern:

Be it known that I, ALVA R. MERRICK, of 5
Blossburg, in the county of Tioga and State
of Pennsylvania, have invented a new and
useful Improvement in Head-Rests in Dental
Chairs; and I do hereby declare that the fol-
lowing is a full, clear, and exact description
of the same.

My invention relates to head-rests for dental
10 and other chairs, having for its object to make
provision for the adjustment of the immediate
head-support in all directions on its standard,
and for its adjustment and extension with its
standard in any direction, either laterally or
15 forward and backward or up and down, or at
any desired angle for the purpose, generally
stated, of bringing the rest in any position re-
quired for the occupant of the chair.

In the accompanying drawings, Figure 1
20 represents a side elevation of the complete
head-rest and its supporting standard. Fig. 2
shows the head-rest and supporting standard
with parts of the clamps removed. Fig. 3
shows in perspective the rest in laterally-ex-
25 tended position. Fig. 4 shows section of the
clamp.

In these drawings, A represents an ordinary
standard adjustable vertically and by rotation
in an ordinary clamp, B, adapted to be attached
30 to a chair, and which, with the standard A, may
be changed for any other suitable means for
supporting the rest and its adjustable standard
and joints to the chair. The top of the stand-
ard A is perforated and flattened, as shown at
35 a, and preferably also has a shoulder, b. To
this is attached a clamp, C, composed of two
parts, d d, both having a hole corresponding
to that in the top of the standard, and adapted
40 to receive the clamping-bolt e. The parts d
of the clamp C have nearly circular portions
1, which fit to the sides of the flattened top of
the standard A, allowing the clamp to swing
45 through a semicircle on the bolt e. On these
parts d d are extensions 2 2, in which are
grooves forming, when the parts are brought
together, a hole to receive the standard D, to
which the rest F is attached. The standard
50 D is round, and fitted to the hole in the ex-
tensions 2 2, so that it may slide or turn there-
in. The parts are so adjusted that by turning
the nut on the pivoting-bolt both the flattened

head of the standard A and the round part of
the standard D are clamped at the same time.
Thus any desired elevation in the limits of its
length may be secured, and also any desired 55
angle, as illustrated in Fig. 1 in full and dot-
ted lines. By this construction the rest may
be extended above or into the chair to suit
either a tall person or a child, and it may also
be tipped to any desired angle in relation to 60
the chair-back. The top of the standard D is
also flattened, as shown at a', and has a shoul-
der, b'. To it is attached a clamp, C', exactly
of the same form as the clamp C, and held to
the standard by a bolt in the same manner as 65
above described. The extensions 4 4 of this
clamp have grooves fitted to receive and hold
the shank f, fixed to the plate of the head-rest
proper, F. On this shank the head-rest F
may rock laterally; but it is clamped by the 70
tightening-nut 5, which at the same time causes
the clamp to grip the flattened top of the stand-
ard D. On the bolt, therefore, of this stand-
ard and clamp the rest F may turn to adjust
75 the inclination thereof to front or rear, while
the rest is adjusted laterally on the shank f or
turned on the joint-standard D, which turns
in its clamp C. By turning the standard A
the standard D may be made to face to the
right or left, and then the latter may be 80
brought down to a horizontal position or to
any angle desired, and by slipping the stand-
ard D in its clamp the head-rest may be ex-
tended to the side, as it is illustrated in Fig. 3.
When brought to this position, the rest is still 85
capable of adjustment in all directions. It
will thus appear that the rest F is connected
to its support A or to any similar or suitable
support by two clamp-joints (which allow uni-
versal adjustment of the rest) combined with 90
a slip-joint. The pivots of the upper clamp-
joint are the shank f and the bolt of the clamp,
whereby vertical and lateral adjustment of
the rest is permitted. The lower clamp-joint
has for its pivots the clamp-bolt and the turn- 95
ing standard A. The slip-joint is formed by
the standard D and its clamp-socket, which
also allows the standard D to turn.

As before intimated, the standard A may be
vertically adjustable or not; but I prefer to 100
make it thus adjustable.

I do not limit myself in respect to the form

of the rest F, nor as to the precise form of the clamps, as they may be modified to allow the universal movement and the clamping; but the form shown of the joints and clamps is 5 preferred.

The nuts may be adapted to a wrench, as shown, or be made as ordinary thumb-nuts.

I am aware that it is not new to employ ball-and-socket joints and various other devices for 10 the purpose of permitting the necessary adjustment of the head-rest; and I am also aware that a vertically-adjustable supporting-standard for the rest is also old, and I do not claim, broadly, these ideas.

I claim as my invention—

In combination with the head-rest having a shank, f, a clamp, C', having the two parts adapted to clamp the flattened head of the standard and the shank f, and the bolt and the nut, all substantially as described.

In testimony whereof I have signed my name to this specification in the presence of two subscribing witnesses.

ALVA R. MERRICK.
